UNITED STATES PATENT OFFICE.

OTTO PETERMANN, OF GROTON, NEW YORK, ASSIGNOR TO CORONA TYPEWRITER COMPANY, INC., OF GROTON, NEW YORK, A CORPORATION OF NEW YORK.

TYPEWRITING-MACHINE.

1,356,825.

Specification of Letters Patent. Patented Oct. 26, 1920.

Application filed June 2, 1917. Serial No. 172,378.

To all whom it may concern:

Be it known that I, OTTO PETERMANN, a citizen of the United States, and resident of Groton, county of Tompkins, and State of New York, have invented certain new and useful Improvements in Typewriting-Machines, of which the following is a specification.

This invention relates more particularly to key actions of front-strike, visible typewriting machines.

One of the principal objects of the invention is to provide a key action which has a very easy and uniform touch and in which the type bars have an upward and rearward accelerated movement.

Another object of the invention is to so construct the key action that it will form an efficient rebound lock to effectively hold the type bar against any rebounding motion after the bar has returned to its point of rest. By providing an effective rebound lock any form of noiseless cushioning material may be used as a stop to receive the blow or impact of the type bar on its return from its printing movement. In typewriting machines which are not provided with a rebound lock the type bars frequently so move in rebounding from the type rest that when adjacent type bars are actuated in succession they are liable to interlock. For this reason, it heretofore, has not been possible to use a soft noiseless cushion or pad on the type rest.

A further object of the invention is to provide simple means for adjusting the various parts of the type bar action and to dispense with the usual form of turn buckle adjustment between the key lever and the type bar.

Other objects of the invention are to provide a simple and efficient key action in which substantially all the parts may be punched from sheet steel or other suitable material; to provide means whereby the parts of the key action may be readily made and assembled, and to provide a key action occupying a minimum amount of space to thereby particularly adapt it for small portable typewriting machines.

In the drawing, Figure 1 is a side elevation of a key action, the supporting parts and the platen being shown in sectional view;

Fig. 2 a similar view showing the type bar in its printing position against the platen;

Fig. 3 a horizontal sectional view on the line III—III of Fig. 1;

Fig. 4 a fragmentary plan view of a key action for a type bar located at the left hand side of the machine;

Fig. 5 a vertical transverse sectional view on the line V—V of Fig. 4; and

Fig. 6 a view similar to Fig. 1, showing a key action for a type bar located at the right hand side of the machine.

Referring to the various parts by numerals, 1 designates the platen which may be supported on any suitable form of carriage; 2 the type bar segment which forms the support for the type bars, said support being of any suitable form or construction, and 3 the type rest, said rest being provided with a suitable soft cushioning material 4. The type bar 5 is mounted at its rear end upon a pivot 6, and carries at its forward end a type head 7, which, as shown in the drawing, is provided with three printing characters. It is manifest that the type head may be provided with any suitable number of printing characters. Below the type bar, near its rear end, is suitably supported the key lever fulcrum bar 8, said bar being preferably located close to the lower edge of the type bar in order that the key action will occupy a small space and be adapted for use in small portable typewriting machines. The key lever 9 is notched on its under side at its rear end, as at 10, to receive the edge of the fulcrum bar, as shown clearly in Fig. 1. The fulcrum bar is perforated to admit of the passage of the rear end of the key lever. The forward end of the key lever extends upwardly and is provided with the usual finger key 11. Near its forward end the key lever is provided with an upwardly extending vertical part 12 which is adapted to engage the under side of a cushioning bar 13, the said bar limiting the upward movement of the key lever and holding said lever in its normal or at-rest position. Extending rearwardly from the part 12 is a bendable, substantially horizontal adjusting prong 14. To the forward end of this prong is pivoted an upwardly extending link 15, the upper end of which is broadened and provided with a horizontal flange 16 at right angles to the longitudinal line of the link.

A bell crank lever 19 is pivoted on an upwardly extending fulcrum prong 17 formed integral with a sheet metal segment 18. The fulcrum prong is in the form of a twisted 5 tooth integral with a flange on the sheet metal segment. It will be observed that the fulcrum-support 18 is in the form of a sheet-metal bar of channel form, the two longitudinal edge-flanges extending upwardly, one 10 of them being deeper than the other in order to afford sufficient metal to form the upwardstanding ears 17, these ears being formed by vertically slitting the flange at intervals and twisting the lugs thus formed so that they 15 will lie at an angle with reference to the supporting-bar. This results in a stiff and light fulcrum-bar which can be manufactured at a minimum cost and which will have a minimum weight. The bell crank 20 lever 19 is formed with an upwardly and forwardly extending arm 19^a, and with a rearwardly extending arm 19^b. The upwardly and forwardly extending arm of 25 said lever is formed with a large aperture 20, the lower wall 21 of said aperture forming a rearwardly and downwardly extending curved bearing surface. The flange 16 of the link 15 extends laterally through the aperture 20, its under side, in the normal 30 at-rest position of the key action, engaging the forwardmost point of the bearing surface 21, as shown clearly in Fig. 1. As the key lever is depressed the flange 16 of the link 15 progressively engages said bearing 35 surface, the point of engagement moving toward the pivotal point 22 of the lever. It is, therefore, manifest that as the key lever is depressed the leverage is greatest on the arm 19^a at the beginning of the movement, and 40 gradually grows less as the link moves downwardly, and that, therefore, the speed of movement of the lever 19 will be gradually accelerated from the beginning of the downward movement of the key lever to the 45 completion of said movement. The lateral flat flange 16 of the link 15 is provided with lugs 16^a at its forward and rear ends which engage the face of the sub-lever 19 at the side opposite the link 15, thereby locking the 50 link 15 against lateral withdrawal from the hole 20 in the sub-lever; and, to hold the rocking flange 16 against fore-and-aft sliding movement on the rocker bearing 21, the front and rear walls of the hole 20 are positioned so as to engage the forward and rear edges of the flange 16, thereby permitting the flange to have a free rocking movement 55 on the bearing 21, but at the same time preventing it being dislocated therefrom. This 60 forms a very, simple pivotal, leverage-varying connection between the link 15 and the sub-lever, which connection will not require any screws or pivots or other parts requiring machine-finishing.

65 The rear end of the type bar is formed

with a short downwardly extending arm 23, and said arm is connected to the arm 19^b of the lever 19 by a horizontal link 24. The points of connection between the arm 23, link 24 and arm 19^b of the bell crank lever, 70 are in a direct line with the center of the pivot 22 of said lever when the parts are in their normal at-rest position, as shown clearly in Fig. 1. When the parts are in the position just described the type bar cannot 75 be moved upwardly except through a downward movement of the key lever. Any tendency of the type head to move upwardly is prevented by the arm 23, link 24 and lever arm 19^b, because the forward thrust of the 80 arm 23 will be transmitted directly to the center of the pivot 22 of the lever 19 and there will be no upward movement of the type bar. These parts are on centers and are locked against movement through the type 85 bar. It is manifest that this will effectually prevent any rebound of the type bar after it has moved back to its at-rest position. Connected to the bell-crank lever and the key lever fulcrum bar is a spring 25 which 90 returns all the parts to their normal at-rest positions upon the release of the key lever. 26 indicates a universal bar of any suitable construction and which is adapted to be engaged by the key lever as it is depressed. 95

The upwardly extending fulcrum prong 17 supporting the lever 19, may be readily bent forward or rearward by any suitable device, in order to properly adjust the connection between the rearwardly extending 100 arm 19^b of the lever 19 and the forward end of the link 24. By providing this bendable fulcrum prong proper adjustment may be made between the lever 19 and arm 23 of the type bar without the necessity of using any 105 other form of adjusting device, such, for instance, as the ordinary and well-known turn buckle. In order to secure the proper adjustment between the key lever, the link 15 and the bearing surface 21 of the bell-crank 110 lever, the prong 14 of the key lever is bendable vertically. It is, therefore, to be noted that all of the necessary adjustments between the several parts of the key action may be secured by bending suitably arranged lugs or prongs, thereby avoiding the use of screws or other similar devices which are liable to be jarred out of proper adjustment in the use of the machine. This 115 method of adjusting is especially advantageous in securing the proper positions of the parts to lock the type bar against rebound.

In Fig. 2 the key action is shown as having been operated to throw the type head 120 on the type bar to the printing point on the platen. The shifting of the point of engagement between the flange 16 and the bearing surface 21 of the lever 19 is clearly shown in this figure, the said flange being 125

in engagement with the point of the bearing surface 21 which is nearest the pivot 22 of the lever, whereas, as hereinbefore pointed out, in Fig. 1 the said flange is in engagement with that portion of the bearing surface which is farthest from the said pivot. It is manifest, therefore, that as the key lever is depressed the motion transmitted to the type bar will be greatly accelerated toward the completion of the printing movement. It is also manifest that at the start of the key lever movement the type bar movement will be slow but will respond to a very light touch. By reason of the disposition of the link 24 and arm 19^b of the bell-crank lever 19 there must be a slight movement of the lever 19 before there can be any upward and forward movement of the link 24. This also contributes to the ease of the key action.

By reason of the arrangement of the arm 19^b of the bell-crank lever, the link 24 and the arm 23 of the type bar, the type bar will be given a progressively accelerated movement toward the platen. It is manifest that as the arm 19^b moves upwardly, its travel away from the pivotal point of the type bar is progressively accelerated, and that consequently the type bar will be given the described accelerated movement. It is clear, therefore, that the acceleration of the type bar will be due, first to the shifting of the point of engagement between the link 15 and the bearing surface 21 of the bell-crank lever, and second by reason of the upward and forward movement of the arm 19^b of the said lever. By reason of this construction and arrangement of the parts the key stroke may be made reasonably short and the leverage of the bell-crank lever may be of considerable length at the beginning of the key stroke, thereby resulting in a very easy key action.

In the drawing the movement of the type bar and the key lever is indicated by numerals and dotted lines. The downward movement of the key lever is indicated by the numerals 0, 1, 2, 3 and 4, the horizontal lines adjoining said numerals indicating equal parts of the downward travel of the said lever. The upward movement of the type bar is indicated by the numerals 0, 1, 2, 3 and 4, the spaces between said numerals indicating the distances traveled by the type bar during the movement of the key lever through the spaces between corresponding numerals. It will be noted that the upward movement of the type bar corresponding to the downward movement of the key between the numerals 0 and 1, is very much less than the upward movement of the type bar corresponding to the downward movement of the key between the numerals 1 and 2; and that the greatest upward movement of the type bar results from the downward movement of the key between the numerals

3 and 4, so that there is a progressive acceleration of the type bar from its point of rest to the platen.

It is manifest that the locking action between the type bar, link 24 and bell-crank lever 19, may be secured by arranging the point of connection between the link 14 and the arm 19^b slightly below a direct line drawn between the center of the pivot 22 of the bell-crank lever and the point of connection between the rod 24 and the arm 23 of the type bar. This arrangement of the parts, while effective, will require a slightly greater lost motion in the bell-crank lever before the movement thereof will actuate the type bar. While the parts in this position will be slightly off centers, it will, of course, be understood that the same result of locking the type bar against rebounding will be secured.

Features of invention disclosed herein but not claimed, are claimed in my co-pending companion application, Serial No. 172,854, filed June 5, 1917.

What I claim is:

1. In a key action the combination of a type bar, a key lever, a bell-crank lever having an upwardly and forwardly extending arm provided with an aperture the lower wall of which forms a downwardly and rearwardly extending bearing surface, the other arm of said lever extending rearwardly substantially horizontally, a link pivotally connected to the key lever and formed with a substantially horizontal flange at its upper end, said flange extending through the aperture in the bell-crank lever and engaging the said bearing surface, and a substantially horizontal link connecting the rearwardly extending arm of the bell-crank lever to the type bar, the points of connection between the link, type bar and bell-crank lever being in a substantially horizontal line and on centers, whereby the type bar will be locked against rebound from its at-rest position.

2. In a key action the combination of a type bar, a key lever, a bell-crank lever having an upwardly and forwardly extending arm provided with an aperture the lower wall of which forms a downwardly and rearwardly extending bearing surface, the other arm of said lever extending rearwardly substantially horizontally, a link pivotally connected to the key lever and formed with a substantially horizontal flange at its upper end, said flange extending through the aperture in the bell-crank lever and engaging the said bearing surface, means carried by the key lever link to prevent its accidental disconnection from the bell-crank lever, and a substantially horizontal link connecting the rearwardly extending arm of the bell-crank lever to the type bar, the points of connection between the link, type bar and

- bell-crank lever being in a substantially horizontal line and on centers, whereby the type bar will be locked against rebound from its at-rest position.
5. In a type-bar action, a sub-lever provided at one end with an upwardly-facing convexed bearing surface and upwardly-extending edges at the forward and rear ends of said bearing surface, and a link adapted
- 10 to connect the sub-lever and key-lever provided with a lateral flange adapted to rock on said convexed bearing surface and provided with lugs extended fore-and-aft to engage said upwardly-extending edges to
- 15 hold said flange from disconnection with said bearing.
4. In a type-bar action, a sub-lever having a hole formed in one end, said hole having a bottom edge convexed upwardly and
- 20 its front and rear edges bending upwardly
- from said convexed lower edge, and a link for connecting the sub-lever to a key-lever and having a flange extending through said hole adapted to rock on said upwardly-convexed edge and provided with lugs extending fore-and-aft to engage said upwardly-extending edges to thereby detachably lock the flange to the sub-lever.
5. In a key action the combination of a type bar, a key lever formed with a rearwardly extending bendable prong, a bell-crank lever, a link connected to the bendable prong on the key lever and having a floating or variable connection with the bell-crank lever, and a link connecting the bell-crank lever to the type bar.

This specification signed this 24th day of May, A. D. 1917.

OTTO PETERMANN.
